UNITED STATES PATENT OFFICE.

THOMAS RAE, OF SYDNEY, NEW SOUTH WALES, AUSTRALIA.

POWER-DRIVEN HACKSAW.

1,281,417.

Specification of Letters Patent. Patented Oct. 15, 1918.

Application filed November 20, 1916. Serial No. 132,456.

To all whom it may concern:

Be it known that I, THOMAS RAE, subject of the King of Great Britain, residing at Sydney, New South Wales, Commonwealth of 5 Australia, have invented new and useful Improvements in Power-Driven Hacksaws, of which the following is a specification.

This invention relates to improvements in power driven hack-saws that are provided 10 with automatically controlled lifting devices for raising the saw on its return or non-cutting stroke and it has for its object the provision of simple and easily controlled means whereby such saws will have greater 15 efficiency in use.

The invention is directed more particularly to the means devised for lifting the saw from the work at the completion of the cutting stroke and returning it correctly to 20 the work at the completion of its non-cutting stroke. The invention furthermore embodies novel features of construction whereby the operative parts can be readily adjusted to suit the particular requirements of 25 the work to be performed.

In order that the invention may be readily understood reference will now be had to the accompanying sheets of explanatory drawings, wherein—

30 Figure 1 is a view in perspective of a power hack-saw machine constructed in accordance with the invention, part of the frame work being shown broken away for convenience of illustration.

35 Fig. 2 is a view in perspective of the power driven hack-saw shown in Fig. 1 viewed from the rear side of the machine.

Fig. 3 is a view in side elevation of the operative parts of the invention, part being 40 shown in sectional elevation.

Fig. 4 is a view in end elevation of a friction gripping device that forms part of the means devised for lifting the saw from the work at the completion of its cutting stroke.

45 Fig. 5 is a view in sectional plan taken on the line 5—5 of Fig. 4.

Fig. 6 is a view in cross section taken on the dotted line 6—6 of part of Fig. 6 and drawn to a larger scale than the other views.

50 Fig. 7 is a view in side elevation (partly in section) of a device for releasing the gripping device shown in Figs. 4 and 5.

In these drawings like characters of reference have been employed to indicate similar 55 or corresponding parts in the different views

and the numeral 1 designates a frame upon one end of which is mounted a revoluble shaft 2. The shaft 2 is mounted transversely on one end of the frame 1 and is fitted with a cam 3, a belt pulley 4 and a crank disk 5. 60

An arm 6 is pivoted to a sleeve (not shown) on the shaft 2 and said arm projects toward the opposite end of the frame, and is designed to support a saw carrying bow 7. The said saw-bow 7 is connected by a link 7' 65 to a pin 9 formed on or fitted to the crank disk 5.

The back of the saw-bow 7 is slotted out at 10 on one side to fit over the curved outer end of the arm 6 and the bow is retained on 70 said arm by means of a plate 11. The plate 11 is bolted or otherwise secured to the back of the saw-bow and removable and adjustable wearing strips 12 are provided to take up all wear incident to the bow reciprocating 75 on the arm.

The guide slot 10 and curved portion of the arm 6 curve downwardly in a gradual sweep from each end and forms a long bearing that obviates the slightest vibration. The 80 radial draw motion obtained by the sweep of the curved guide provides for a maximum cutting efficiency with a minimum of pressure and friction as only a few of the saw teeth are kept in touch with the work. 85

One end of the saw-bow is fitted with an adjustable blade holder 13 and the opposite end of the said saw-bow is provided with a pin 14 that is engaged by a hole in the saw blade 15 in the ordinary way. 90

The saw-bow is raised slightly when the saw has completed its cutting stroke and is kept in its raised position until it has furnished its outward or idle stroke when it is again lowered on to the work. 95

The saw-bow is raised by the action of the cam 3 and a lever 16 the former being timed to effect the movements above described. The cam 3 bears against the underside of a roller 17 carried on the lever 16 and the 100 outer end of said lever is pivoted to a bracket 18 on the frame 1. The inner end of the lever 16 is provided with a frictional gripping member that engages a curved bar 19 depending from the saw carrying arm 6. 105

The forward end of the lever 16 is enlarged and bifurcated to fit around the curved bar 19 and the sides 20 of the bifurcation are inclined downwardly as shown in Fig. 4 of the drawings. 110

The inclined sides of the bifurcation in the end of the lever 16 are fitted with steel plates 21 and rollers 22 are arranged horizontally between the plates 21 and the curved bar 19. 5 The rollers 22 are supported between the enlarged ends of oppositely disposed spindles 23 and 24 that are reciprocatingly mounted in top and bottom cover-plates 25 and 26 respectively, fitted to the bifurcated end of the 10 lever 16.

The rollers, normally, are pressed downward by the action of compression springs 27 fitted to the spindles 23. The cover-plates 25 and 26 are securely fastened to the inner 15 end of the lever by means of bolts 28. A front cover-plate 29 is fitted to the inner end of the lever 16 by means of screws 30 to completely house the rollers 22 and insure them being retained in their correct 20 operative positions.

When the outer end of the lever 16 is lowered the lower ends of the bottom spindles 24 are brought to bear upon tappets 31 that cause said spindles 24 to rise and release the rollers 22 at the completion of each 25 return or idle stroke and thereby enable the saw to drop slightly to take the cut.

The tappets 31 screw into sleeves 32 for purposes of adjustment and the said sleeves 30 are free to rise and fall in a supporting bracket 33 fitted to the machine frame. A lever 34 pivoted on the bracket 33 is arranged to raise the tappets 31 by hand to free the gripping rollers 22 and enable the 35 saw to be lowered into position on the work at the commencement of operations.

In order to prevent the saw-bow from dropping too rapidly and endangering the parts—as in the event of a saw breaking—a 40 dash pot comprising an ordinary cylinder 35 is located beneath the frame. A piston 36 is fitted in the cylinder 35 and is adapted to rise freely and be retarded on the down stroke.

45 The upper end of a piston rod 37 is formed with a laterally projecting pin 38 that is loosely engaged by a slot 39 formed in the lower end of a rod 40 having its upper end pivoted to the arm 6. The slot 39 is slightly 50 longer than the clearance lift of the saw so that said saw may drop to each successive cut in advance of the slowly descending piston.

The lever 16 is provided with an adjustable rod 41 to the lower end of which is connected one end of a tension spring 42 the opposite end of which is secured to a stud 43 fitted to the machine frame.

60 The arm 6 is provided with two vertical posts 44 upon which is mounted a bar 45 having weights 46 secured adjustably thereon. The weights 46 are secured in position on the bar 45 by set screws 47 and by adjusting the positions of said weights a greater 65 or lesser pressure can be placed on the saw.

The machine is fitted with a vise 48 to hold the material to be cut and a gage 49 to determine the length to be cut from a bar of metal or the like. Guide pins 50 are provided to prevent the severed portion of a 70 rod or bar coming into forcible contact with the saw and damaging it.

When the saw has reached its lowest position after cutting through a bar or the like, the inner end of the bow comes into contact 75 with and operates a lever 51 that is connected to a clutch (not shown) on the shaft. The clutch can be put into or out of gear in the ordinary way by operating a hand lever 52.

The base of the frame is made hollow to contain a liquid that will act as a lubricant and keep the saw cool when in operation. A small pump 53 is provided to force the liquid from the base of the frame through a pipe 85 54 to a flexible pipe 55 that directs the liquid on to the saw and material being cut by the same. The pump 53 is driven by belt and pulley mechanism 56 from the shaft 2.

The liquid sprayed on to the saw by the 90 pipe 55 flows into a channel 57 formed around the frame of the machine and it is directed from said channel through an opening 58 back to the hollow base of the machine.

95 The invention is extremely simple in construction and operation and in use will be found thoroughly efficient for the purpose for which it has been devised.

What I do claim is:—

100 1. A power hack-saw comprising a frame, a revoluble shaft mounted transversely on the frame, an arm pivoted at one end on the shaft, a saw-bow reciprocatingly mounted on the pivoted arm, a crank disk on the 105 shaft, a link connecting the crank disk to the saw-bow, a bracket on one end of the frame, a lever pivoted to the bracket, a roller on the lever, a cam fitted to the shaft and bearing on the under-side of the roller, a curved 110 bar fitted to and depending from the pivoted arm, an enlarged inner end on the lever, a mortise in the enlarged end of the lever to accommodate the curved bar, friction gripping devices located within the enlarged end 115 of the lever to engage the curved bar, and means for releasing the friction gripping devices, substantially as described.

120 2. In a power hack-saw, a frame, a horizontal shaft, a pivoted arm, a saw-bow reciprocatingly mounted on the arm, a lever pivoted at one end to the frame, a mortise in the free end of the lever having inclined sides, a curved bar depending from the pivoted arm and passing through the mortise in 125 the lever, rollers between the sides of the curved bar and the inclined sides of the mortise, spindles having enlarged heads supporting the rollers in the mortise, springs exerting a downward pressure on the rollers, 130

and means for exerting an upward pressure on the rollers to release the same, substantially as described.

3. In a power hack-saw, a frame, a horizontal shaft revolvably mounted on the frame an arm pivoted at one end, a saw-bow reciprocatingly mounted on the free end of the arm, a bracket on the frame, a lever pivoted at one end to the bracket, a friction gripping device on the free end of the lever, a curved bar depending from the pivoted arm and engaged by the friction gripping device, a roller on the lever, a cam on the shaft bearing against the underside of the roller, and means for intermittently releasing the friction gripping device, substantially as described.

4. In a power hack-saw, a frame, a horizontal shaft mounted transversely on the frame, an arm pivoted at one end, a saw-bow reciprocatingly mounted on the free end of the arm, a bracket on the frame, a lever pivoted at one end to the bracket, means for raising and lowering the free end 25 of the lever, a vertical mortise in the free end of the lever having inclined sides, wearing plates fitted to the inclined sides of the mortise, a curved bar depending from the pivoted arm and passing through the mortise in the lever, rollers located between the sides of the curved bar and the sides of the mortise, spindles arranged vertically above and below the rollers to support the same within the mortise, springs exerting a downward pressure on the rollers, and adjustable tappets beneath the lower spindles, substantially as described.

5. In a power hack-saw, a pivoted arm carrying a reciprocatingly mounted saw-bow, a pivoted lever having a vertical mortise therein formed with inclined sides, a curved bar depending from the pivoted arm and passing through the mortise, rollers in the mortise, vertical spindles supporting the rollers, adjustable tappets located beneath the spindles, a pivoted lever supporting the tappets, and a bracket supporting the tappet supporting lever, substantially as described.

50 6. In a power hack-saw, a pivoted arm carrying a reciprocatingly mounted saw-bow, a saw on said saw-bow, a curved bar depending from the pivoted arm, a pivoted

lever having a vertical mortise therein formed with inclined sides, a pair of rollers 55 in the mortise arranged to engage the curved bar on the pivoted arm, means for raising and lowering the lever and means for throwing the rollers out of engagement with the curved bar while the saw is moving on its 60 working stroke, substantially as described.

7. In a power hack-saw, a frame, a shaft revolvably mounted on the frame, a pivoted arm, a saw-bow reciprocatingly mounted on the arm, weights adjustably secured to the 65 pivoted arm, a bracket on one end of the frame, a lever pivoted at one end to the bracket, a roller on said lever, a cam fitted to the shaft and bearing against the underside of the roller, a friction gripping device on 70 the free end of the lever, a curved bar depending from the pivoted arm and passing through the gripping device, a crank on the shaft, a link connecting the crank to the saw-bow, a cylinder fitted to the frame, a piston in 75 the cylinder, a rod having its lower end loosely connected to the piston and its upper end pivoted to the pivoted arm, and a spring connection between the lever and the frame, substantially as described.

8. In a power hack-saw, a frame, a shaft mounted transversely on the frame, an arm having one end pivoted to the shaft and the opposite end formed with a regular downward curve, a saw-bow having a curved recess slidably engaging the curved part of the pivoted arm, means on the saw-bow for detachably securing a saw thereto, weights secured adjustably to the pivoted arm, a bracket on one end of the frame, a lever having one end pivoted to the bracket and its opposite end provided with a friction gripping device, a roller on the lever, a curved bar depending from the pivoted arm and engaged by the gripping device, a cam 95 on the shaft arranged to bear against the underside of the roller on the lever and a crank on the shaft operatively connected to the saw-bow, substantially as described.

In testimony whereof I have signed my 100 name to this specification in the presence of two subscribing witnesses.

THOMAS RAE.
